UTILITY KNIFE

Filed April 10, 1931

INVENTOR
I. S. BODKIN,
BY
A. P. Bourne
ATTORNEY

UNITED STATES PATENT OFFICE

IRVING S. BODKIN, OF NEW YORK, N. Y., ASSIGNOR TO GILLETTE SAFETY RAZOR COMPANY, OF BOSTON, MASSACHUSETTS, A CORPORATION OF DELAWARE

UTILITY KNIFE

Application filed April 10, 1931. Serial No. 529,158.

This invention relates to utility knives, and more especially to a member adapted to receive a safety razor blade and conveniently hold the same in either a shielded and carrying position or an exposed and working position. I am well aware that many devices for this general purpose have been heretofore known and it is therefore the primary object of my invention to provide an improved and more convenient member of this nature and for the purpose stated.

My invention relates more particularly to a safety razor blade utility knife member which is so constructed as to provide a relatively thin and small vest pocket article, of light weight, easily adjustable from carrying position to working position and vice versa, and which is convenient to carry in the closed position and so extended in its working position as to permit easy handling thereof and provide a knife quite suitable for general utility purposes. The construction embodies a relatively flat case for housing a blade holder which in turn is adapted to support the blade. The holder is slidable within the case to and from the carrying and working positions and the construction is such that the parts, including the guiding and retaining elements between the case and holder, may be most conveniently and economically stamped from sheet metal. The production of such an improved device of this nature and for the purpose stated comprises a further object of my invention.

In the accompanying drawings I have illustrated one specific embodiment of my invention but it will be understood that the invention can be otherwise embodied and that the drawings are not to be construed as definite or limiting the scope of the invention, the claims appended hereto being relied upon for that purpose.

Referring to the figures of the drawings:

Fig. 1 is a front elevation of one embodiment of my invention in closed position.

Fig. 2 is a sectional view taken on line 2—2 of Fig. 1.

Fig. 3 is a view like Fig. 1 but showing the device in open position.

Fig. 4 is an elevation of the blade holder

and showing a blade being removed therefrom.

Fig. 5 is a sectional view taken on line 5—5 of Fig. 4.

Fig. 6 is a sectional view taken on line 6—6 of Fig. 3.

Fig. 7 is an enlarged fragmentary sectional view taken on line 7—7 of Fig. 3.

Fig. 8 is an enlarged fragmentary view taken on line 8—8 of Fig. 4.

Referring now to the embodiment of my invention which is illustrated in the accompanying drawings, 10 designates a case within which is slidably mounted a holder 12 adapted to receive and carry a safety razor blade 14. While the case and holder may be constructed in various forms and by various methods, they are capable of very simple and economical construction and I have preferred to herein illustrate the same as thus made, preferably of sheet metal and by well known stamping operations. Thus, while I shall now proceed to define the specific construction illustrated, it will be understood that the same is by no means to be construed as a limitation on the invention.

The case 10, as illustrated, is formed from a flat sheet, preferably of metal, bent U-shaped upon itself to provide two flat and relatively broad sides connected together at an edge 16. One end and a portion of one side edge of the case is substantially closed by inwardly turned flanges 18 and a bail 20 for attaching a chain may be connected to this end. The other end of the case and the adjacent longitudinal edge portions opposite the closed edge 16 are open for permitting the passage of the holder 12.

The holder 12 is likewise formed from a flat sheet bent U-shaped upon itself to provide two side portions for securing and holding the blade 14 therebetween. The connecting edge of the holder is relatively wide in the nature of a bead 22, whereby an outward or flaring effect of the holder sides may be provided, and the co-operating portion 24 of the case adjacent to its edge 16 is likewise relatively wide whereby to receive the bead and permit longitudinal and transverse movement of the holder within the case. The

sides of the case outwardly of the portion 24 are parallel and engage flatwise against the side portions of the holder.

The closed and open positions of the holder within the case are shown in Figs. 1 and 3 respectively, the holder being movable diagonally of the case longitudinally and edge-wise through an open end and side thereof to and from these positions. This movement is facilitated and the holder is guided and held securely relatively to the case by a co-operating guiding connection between adjacent sides of the case and holder elements. As illustrated, the guides of this connection are preferably integral with these elements and may comprise co-operating diagonally disposed ribs stamped therefrom. The rib 26 of the case 10 is shown pressed outwardly in groove-like form and the rib 13 of the holder 12 is pressed outward and is slidable longitudinally in the rib 26. Said ribs retain the case and the holder in different positions of said parts. Stops 26a are shown located at the ends of the groove of rib 26, said stops being in the path of rib 13 to be engaged thereby to limit the longitudinal movement of the holder within the case. The holder may be drawn outwardly by grasping a finger piece 28 and may be retained in two positions by a releasable detent comprising a resilient button 30 carried by the holder and engageable within two relatively spaced openings 32 and 32a in one side of the case. When the holder is in its extended position, (Fig. 3), the blade edge is exposed for use beyond the case. The co-operation of the ribs in conjunction with the diagonal or inclined positions thereof resist thrusts against the blade edge in use. When the holder is pushed inwardly in the case the blade edge will be concealed and shielded by the case, as in Fig. 1.

As shown in Fig. 7, the button 30 is an integral part of the inwardly extended end 45 portion of the side 15 of the holder. The adjacent end of the other side 15a of the holder is attached to the side 15 by means of a flange 36 thereon entering a slot formed in the said side 15. The outer edge portions 50 of the side portions of the holder normally spread apart or flare, as shown in Fig. 5, and, when in said position with the holder drawn outwardly as in Fig. 3, the blade can be removed and another inserted, the side portions being notched at 38 for assisting this operation. These edge portions of the holder are held clamped against the blade by the finger piece or gripper 28, shown as a U-shaped member engaged over the outer end 60 and the adjacent side portions of the holder. The gripper 28 is held in sliding position on the holder by means of a retaining finger 40 struck out therefrom and extending through aligned slots 42 in the side portions 65 of the holder. The gripper member 28

serves the double function of causing the side walls of the holder to grip and retain the blade securely in the holder and providing a finger grip for adjusting the holder 12 relatively to its case 10, and, to Letter serve these functions, the member 28 is preferably knurled or roughened as illustrated. When the gripper 28 is in the position shown in Figs. 1 and 2 it will cause the side portions of the holder to grip the blade, (Fig. 6), and when the gripper is in the position shown in Fig. 4 the side portions of the holder will release the blade to facilitate removal and replacement. The case also may be notched at 44.

The inner end of the holder side 15 can be sharpened and used as cigar cutter, taking advantage of the aperture 32 to receive the cigar end, (Fig. 7).

The parts as illustrated are simple but substantial and the arrangement is such that the device can be made economically and will serve its intended function with great facility.

Having thus described my invention what I claim as new and desire to secure by Letters Patent of the United States is—

1. A utility knife comprising a case having sides spaced apart and open along two adjacent and relatively angular edges, a blade holder between said sides and having relatively spaced side portions for holding a blade therebetween, means providing a guiding connection between the case and holder whereby the holder can be moved through an end and side of the case to and from positions shielding the cutting edge of the blade within said sides and exposing the same through and outside of said open edges, and means for retaining the holder in said positions.

2. A utility knife comprising a case having spaced sides open along one end and one side of the case, a blade holder slidable between said sides of the case and through the said open end and side thereof, and co-operative means between the case and the holder guiding the latter for movement through said open end and side of the case, said co-operative means being disposed diagonally with respect to the length of the case.

3. A utility knife as set forth in claim 2 in which the guiding means comprise a groove-like rib on the case and a rib on the holder slidable in the first-named rib.

4. A utility knife as set forth in claim 2 in which the guiding means comprise a groove-like rib on the case, said rib having stops at its ends, and a rib on the holder slidable along the first-named rib, said second-named rib being in position to engage said stops to limit the movement of the blade holder into and from the case respectively.

5. A utility knife comprising a case hav-

- ing relatively spaced sides integrally connected along one edge, said case being provided with two relatively spaced holes, a blade holder between said sides and having 5 two relatively spaced and integrally connected side portions for holding a blade therebetween, means integral with the case and holder providing a guiding connection therebetween whereby the holder can be 10 moved to and from positions shielding the cutting edge of the blade within said sides and exposing the same outside thereof, and resilient means carried by the holder and engageable with the two relatively spaced holes 15 in said case for retaining the holder in said two positions.
6. A utility knife comprising a case having relatively broad sides spaced apart and open along two adjacent and relatively angular edges, a blade holder between said 20 sides having relatively spaced side portions for holding a blade therebetween, a member movably mounted on one end of the holder and adapted in one position to permit separation of the side portions for the insertion of a blade and in another position to bind the portions together into holding contact 25 with the blade, means providing a guiding connection between the case and holder whereby the holder can be moved to and from positions shielding the cutting edge of the blade within said sides and exposing the same outside thereof, and releasable means for retaining the holder in said two positions.
- 30 7. A utility knife comprising a case having relatively broad sides spaced apart and open along one edge, a blade holder between said sides and having relatively spaced sides connected along one edge, said holder being provided with a slot, a gripper engaging over one end and the adjacent sides of the 35 holder and having a retaining finger engaging in the slot in said holder whereby the gripper may be slid from a position adjacent to the one edge toward the opposite edge, the gripper being adapted in one position to permit separation of the holder sides for the insertion of a blade and in another position to bind said portions into 40 holding engagement with the blade, means providing a guiding connection between the case and holder whereby the holder can be moved to and from positions shielding the cutting edge of the blade within said sides and exposing the same through and outside of said open edge, and releasable means for retaining the holder in said two positions.
- 45 8. A utility knife as set forth in claim 7 in which the outer portions of the sides of the holder are normally outwardly flaring.
9. A utility knife comprising a substantially U-shaped metal case having the sides thereof more widely spaced apart adjacent to their connected edges than at their outer portions, 50 a substantially U-shaped blade holder be-
- tween said sides and relatively wider at the connected edges thereof than at their outer portions, and adapted to slide between said widely spaced portions of the case sides, the holder being diagonally slideable within the case, means providing a connection between the case and holder whereby the holder can be moved diagonally of the case to and from positions shielding the cutting edge of the blade within said sides and exposing the same outside thereof, and releasable means for retaining the holder in said two positions. 70
10. A utility knife comprising a case having sides spaced apart and open along one edge, a blade holder between said sides and having relatively spaced side portions for holding a blade therebetween, means providing a guiding connection between the case and holder whereby the entire holder is capable of simultaneous edgewise and longitudinal movement to and from positions shielding the cutting edge of the blade within the sides of said case and exposing the said cutting edge through and outside of said open edge, and releasable means for holding the holder in 75 said two positions. 80
11. A utility knife comprising a case formed from a sheet bent upon itself to form relatively spaced sides connected along one edge, a blade holder between said sides and having relatively spaced side portions for holding the blade therebetween, means providing a guiding connection between the case and holder whereby the entire holder is capable of simultaneous edgewise and longitudinal movement to and from positions shielding the cutting edge of the blade within the sides of said case and exposing the said cutting edge through and outside of said open edge, and releasable means co-operative with 85 the case and the holder for retaining the holder in 90 said two positions. 95
12. A utility knife comprising a case formed from a sheet bent upon itself to form two relatively spaced sides connected along one edge, a blade holder between said sides and formed from a sheet bent upon itself to form two relatively spaced side portions for holding a blade therebetween, diagonally disposed co-operative means between the case and holder providing a guiding connection therebetween whereby the entire holder is capable of simultaneous edgewise and longitudinal movement to and from positions shielding the cutting edge of the blade within the sides of said case and exposing the said cutting edge outside thereof, and releasable means co-operative with the case and holder for retaining the holder in 100 said two positions. 105
13. A utility knife comprising a case formed from a sheet bent upon itself to form two relatively spaced sides connected along one edge, a blade holder between said sides and formed from a sheet bent upon itself to form two relatively spaced side portions for holding a blade therebetween, diagonally disposed co-operative means between the case and holder providing a guiding connection therebetween whereby the entire holder is capable of simultaneous edgewise and longitudinal movement to and from positions shielding the cutting edge of the blade within the sides of said case and exposing the said cutting edge outside thereof, and releasable means co-operative with the case and holder for retaining the holder in 110 said two positions. 115
14. A utility knife comprising a case formed from a sheet bent upon itself to form two relatively spaced sides connected along one edge, a blade holder between said sides and formed from a sheet bent upon itself to form two relatively spaced side portions for holding a blade therebetween, diagonally disposed co-operative means between the case and holder providing a guiding connection therebetween whereby the entire holder is capable of simultaneous edgewise and longitudinal movement to and from positions shielding the cutting edge of the blade within the sides of said case and exposing the said cutting edge outside thereof, and releasable means co-operative with the case and holder for retaining the holder in 120 said two positions. 125
